ATTACHMENT FOR OPERATING TABLES

Julia Fannin Holt, West Palm Beach, Fla.

Application January 25, 1936, Serial No. 60,874

7 Claims. (Cl. 311—10)

This invention relates to attachments for operating tables and more particularly to an attachment for supporting sterilizer trays along either side of the operating table in convenient position for the doctor while he is attending a patient.

An object of the invention is to provide a support for clamping to the operating table and more particularly to one of the other of the stirrup supporting rods thereof so as to support the sterilizing tray in a convenient position above the plane of the table.

Another object of the invention is to provide an attachment for supporting a sterilizing tray with clamping means for clamping it to an operating table and an adjustable clamping means thereon for varying the size of the support accommodating it for different sized sterilizing trays.

Further details, features and objects of the invention will appear in the following description in connection with the accompanying drawing forming a part thereof wherein,

Fig. 1 is a side elevational view showing an operating table with tray supporting means clamped thereon in accordance with my invention,

Fig. 2, a perspective view of the tray supporting means, and Fig. 3 is an elevation of a modified support.

Referring to the drawing an operating table 10 of conventional form is shown wherein the back portion 11 is illustrated in the horizontal position with respect to the seat portion 12 and the leg portion 13 is in an inclined position. The usual form of clamping means for these parts are conventionally represented.

The operating table 10 is provided with horizontally extending stirrup rods 14 at either side, the one to the front only showing and the stirrup removed therefrom. As shown in Fig. 1 a sterilizing tray support, generally designated 15, is shown clamped in a convenient position on this stirrup rod 14 supporting a sterilizing tray 16 at a convenient position above the operating table.

Referring to the perspective view, Fig. 2, this tray supporting attachment 15 is shown in detail and comprises a clamp 17 having a cylindrical aperture 18 therein with upwardly and downwardly projecting slots 19 and a clamping set screw 20. This clamp is adaptable to engage either a cylindrical rod through the cylindrical aperture 18 or a rectangular bar by means of the slots 19, the apertures being so formed as to provide a snug fit on the standard types of oper-

ating tables. When positioned on a table the said set screw 20 is turned so as to hold the clamp in the desired adjusted position.

The upper portion 21 of the clamp supports a horizontal bar 22 and an upright 23 at the top of which is a tray supporting bar 24 which is preferably provided with spaced upwardly extending end members 25 for supporting the handle 26 of a tray 16 as generally indicated in Fig. 1.

On the other end of bar 22 is a clamp 27 with its engaging set screw 28 for holding this clamp in the desired position on bar 22 and as indicated at 29 and 29' the bar is preferably provided with notches for receiving the end of screw 28 so as to definitely locate the clamp in one or more positions along bar 22 for supporting standard sized trays 16, either long trays as shown in Fig. 1 or short trays as provided for by the notch 29. Clamp 27, however, may be secured in other positions along the bar than the two positions defined by the notches as will be readily understood.

Clamp 27 is likewise provided with an upright 23 at the top of which is a supporting bar 24 with spaced forwardly and upwardly extending end members 25.

As shown in Fig. 1 the tray is supported on the bars 24 and it will be seen that the distance between these supports may be adjusted by changing the position of clamp 27 along bar 22 so that sterilizing trays of different lengths may be supported thereby.

Since the stirrup rods on some operating tables are round and on other tables they are flat, it will be seen that the tray support is adaptable for either form. The stirrup on either side of the table, most convenient for the doctor, is removed and the rack is placed on this rod at the desired position and clamped in place. The sterilizer tray is removed from the sterilizer and placed on the rack provided by the supporting bars 24 between which it is suspended. By the provision of this rack the sterilizer tray and instruments are readily accessible to the doctor and he can pick up any instrument he needs without having to ask his assistant for it, or having to reach over for it from the sterilizer or another table. In this way no instrument is touched after sterilization and is most conveniently placed for the doctor while treating his patient.

In Figure 1 the tray support is arranged to hold the tray extended inwardly of the stirrup bar as shown. The stirrup bar can be swung on its support so as to position the tray at any

desired angle with respect to the table 10,—forwardly towards the head of the operating table, laterally outward or rearwardly with respect thereto. However, it is often preferable that this 5 tray support be reversed on the stirrup bar so as to extend the tray outwardly from the end of the stirrup bar. In Fig. 3 of the drawing the tray support 31 is shown in such reverse position on a stirrup bar 32.

10 This tray support 31 is a simplified form of support similar to the one shown in Figures 1 and 2 of the drawing except that it is made to support one standard size tray, the supporting uprights 33 being rigidly secured to the bar 34 instead of being adjustable towards and away 15 from each other. This tray support is similarly provided with a clamp 35 whereby it may be adjusted to any desired position along the stirrup bar 32.

20 Either tray may be positioned in either direction on the bars and they are adaptable to the stirrup bar on either side of the table,—operating or treatment tables—and they provide most 25 convenient attachments for positioning on stirrup bars of such tables.

It will be obvious to those skilled in the art that various changes may be made in this device without departing from the spirit of the invention and therefore I do not limit myself to what 30 is shown in the drawing and described in the specification but only as indicated in the appended claims.

I claim:

1. An attachment for operating tables comprising a sterilizing tray supporting bracket, said 35 bracket consisting of a clamp for securing it to the table, a bar extending horizontally from said clamp, a clamp movable along said bar, and upwardly extending tray supporting members on each of said clamps.

2. An attachment for operating tables comprising a sterilizing tray supporting bracket, said bracket consisting of a clamp for securing it to the table, said clamp having a cylindrical slot 40 therethrough for positioning it on a cylindrical stirrup supporting rod of the operating table, a bar extending horizontally from said clamp, a clamp movable along said bar, and upwardly extending tray supporting members on each of said 45 clamps.

3. An attachment for operating tables comprising a sterilizing tray supporting bracket, said bracket consisting of a clamp for securing it to the

table, said clamp having a slot therethrough for positioning it on either a cylinder or rectangular bar, a bar extending horizontally from said clamp, a clamp movable along said bar, and upwardly extending tray supporting members on each of said clamps. 5

4. An attachment for operating tables comprising a sterilizing tray supporting bracket, said bracket consisting of a clamp for securing it to the table, said clamp having a cylindrical slot 10 therethrough with upper and lower slots for positioning it on a cylindrical stirrup supporting rod of the operating table or on a rectangular bar, a bar extending horizontally from said clamp, a clamp movable along said bar, and 15 upwardly extending tray supporting members on each of said clamps.

5. An attachment for operating tables comprising a sterilizing tray supporting bracket, said bracket consisting of a clamp for securing 20 it to the table, a bar extending horizontally from said clamp, a clamp movable along said bar, said bar having a notch therein for definitely locating said clamp thereon, said clamp having a screw 25 therein for securing the clamp to the bar and engageable with said notch, and upwardly extending tray supporting members on each of said clamps.

6. An attachment for operating tables comprising a sterilizing tray supporting bracket, 30 said bracket consisting of a clamp for securing it to the table, a bar extending horizontally from said clamp, a clamp movable along said bar, and upwardly extending tray supporting members 35 on each of said clamps, said tray supporting members including a bar having separated upwardly extending ends whereby a sterilizing tray is maintained in position thereon.

7. An attachment for operating tables comprising a sterilizing tray supporting bracket, said 40 bracket consisting of a clamp for securing it to the table, said clamp having a cylindrical slot therethrough with upper and lower slots for positioning it on a cylindrical stirrup supporting rod of the operating table or on a rectangular 45 bar, a bar extending horizontally from said clamp a clamp movable along said bar, said bar having a notch therein for definitely locating said clamp thereon, said clamp having a screw therein for securing the clamp to the bar and engageable with said notch, and upwardly extending tray supporting members on each of said clamps. 50
